ABSTRACT

The object of the present invention is to provide a garbage pail having a lid pivotally mounted on a lid mount structure, the lid mount structure having a liner space allowing a liner to be folded over the mouth of the container without obstructing the lid and vice versa.

Said garbage pail comprised of an open mouth container (1) molded substantially of a solid substance, said garbage pail having a lid (4.5) seating on the mouth thereof, pivotally secured to a lid mount structure (3) extending outward from the rear wall of the container, the lid mount structure is formed with a liner space (6) open at the top and sides allowing a plastic liner bag to be folded over the mouth of the container, the lid mount structure is formed with a rearwardly extending wall standoff (5).

Primary Examiner—Joseph Man-Fu Moy

1 Claim, 1 Drawing Sheet

FIG. 1

GARBAGE PAIL

TECHNICAL FIELD

The present invention relates to domestic waste receptacles for the collection, containment and temporary storage of household rubbish and to commercial paper and plastic shopping bags.

BACKGROUND ART

In the present industrialized world it is possible to purchase a vast array of domestic garbage pails. Most household waste pails are used in conjunction with a disposable sanitary liner inserted to line the holding cavity of the container. Though most garbage pails are used inconjunction with disposable liners few are designed and constructed to hold the same open, and prevent refuse from getting between the liner and the inner walls of the container.

DISCLOSURE OF INVENTION

In accordance with the present present invention there is provided a garbage pail comprised of an open mouth container. The mouth of the holding cavity of the container has a four member inwardly folding perimeteral lip for holding open the mouths of paper shopping grocery inserted within the holding cavity open against the interior walls of the mouth of the container to prevent substances disposed within the container from getting outside the liner inbetween the liner and the container.

BRIEF DESCRIPTION OF DRAWINGS

The details of the present invention will be discussed in connection with the accompanying drawing, FIG. 1 which presents an exploded perspective view of a possible embodiment of the present invention, though let it be known that the scope of the invention is not so limited.

BEST MODE FOR CARRYING OUT THE INVENTION

Referring now to the drawing FIG. 1 by reference characters there is shown an open mouth garbage pail 1 of molded plastic. The mouth of the container is molded with a downwardly extending collar 2 thereabout. The collar of the mouth of the container is molded with recessed shelf 3 along the widthwise and lengthwise ends. The opposing lengthwise defining walls of the recessed portions of the mouth of the container are formed with a perforation 4 each, for pivotally seating the integral hinge pins 5 molded at either end of the central length of a pair of liner holding flaps 6, and pivotally securing the liner holding flaps to the lengthwise ends of the mouth of the container. The opposing lateral

defining walls of the recessed portions of the widthwise dimensions mouth of the container are formed with a perforation 7 each, for pivotally seating the integral hinge pins 8 molded at either end of the central length of a pair of liner holding C shaped members 9, and pivotally securing the C shaped liner holding members to the widthwise ends of the mouth of the container. When installing a paper or plastic shopping bag in the holding cavity of the container the lengthwise members are in folded first over the upper lip of the liner bag and the C shaped members are infolded secondly locking the lengthwise members in place, there sandwiching the upper perimetral lip of a liner bag between the inner walls of the mouth of the container and the inwardly folding members of the liner holding lip. The right angled appendages of the C shaped folding members are formed with rectangular cutouts 10 open to the top directly abutting the angle of orientation for suspending the integral handled plastic shopping bags into the container to line the same with the upper lips of the bags sandwiched beneath the inwardly folding members of the liner holding lip.

The present invention possesses the advantage of providing a domestic garbage pail that will except common disposable paper grocery bag and integral handled plastic grocery bags as disposable liners therefor, and will hold the mouths thereof open against the interior walls of the container, thus preventing undesirable material from falling between the liner and the interior walls of the container.

I claim:

1. A garbage pail comprised of a base supporting upwardly extending walls, the upper portions of said walls defining a mouth, rearward portions of said walls having a lid support structure, said lid support structure having a lid pivotally secured thereto, said lid support structure holding said lid stationary in either a closed position covering said mouth or in an open position above said mouth, said lid support structure having at least one liner slot formed therein, open to the top and sides, extending downward significantly below the upper portions of said walls, said lid support structure having wall standoff means extending rearward beyond said lid, thereby providing a garbage pail where a liner can be folded over said mouth and the upper portions of said walls without becoming obstructed by said lid support structure or said lid, or pinched between said lid and said lid support structure, wherein the lid can freely pivot on the lid support structure without obstruction by a rearward wall contacting the garbage pail, said standoff means further providing protection for retaining the lid operably on the garbage pail invention the garbage pail is jostled into a rearward wall.
